(57) CLAIM

I claim the ornamental design for underwear with small inside right pocket, as shown and described.

DESCRIPTION

FIG. 1 is a front perspective view of the underwear with small inside right pocket.

FIG. 2 is a front view thereof.

FIG. 3 is a rear view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an enlarged section view of the small pocket from FIG. 5; and,

FIG. 9 is an enlarged section view of the small pocket from FIG. 6.

The broken lines shown depict portions of the underwear with small inside pocket that form no part of the claimed design.

1 Claim, 4 Drawing Sheets
